UNITED STATES PATENT OFFICE.

EDGAR J. BRYAN, OF RIVERSIDE, CALIFORNIA, ASSIGNOR OF ONE-HALF
TO ALBERT W. MILLER, OF RIVERSIDE, CALIFORNIA.

HAND-TRUCK.

SPECIFICATION forming part of Letters Patent No. 756,096, dated March 29, 1904.

Application filed June 9, 1903. Serial No. 160,690. (No model.)

To all whom it may concern:

Be it known that I, EDGAR J. BRYAN, a citizen of the United States, residing at Riverside, in the county of Riverside and State of California, have invented a new and useful Hand-Truck, of which the following is a specification.

The invention relates to improvements in hand-trucks for moving boxes and various other receptacles and the like.

The object of the present invention is to improve the construction of hand-trucks, more especially that shown and described in Patent No. 714,140, granted to me November 25, 1902, and to provide a simple and comparatively inexpensive truck of this character adapted to dispense with the spring employed in the said patent and capable of having its operating or foot lever arranged so that it cannot come in contact with the supporting-surface in any position in which the truck may be placed.

A further object of the invention is to provide a hand-truck provided with means for clamping the load to be carried and capable of enabling such clamping means to be readily operated to engage and release the load.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective view of a hand-truck constructed in accordance with this invention, the clamping members being open for receiving a load. Fig. 2 is a rear elevation of the truck, the latter being in an upright position and the clamping members being closed. Fig. 3 is a vertical longitudinal sectional view, the truck being in an upright position. Fig. 4 is a sectional view on the line 4-4 of Fig. 3. Fig. 5 is a detail view illustrating the manner of mounting the oscillatory fulcrum-link of the foot-lever.

50 Like numerals of reference designate corre-

sponding parts in all the figures of the drawings.

1 1 designate longitudinal side bars provided at their rear ends with handles 2 and connected by cross-bars 3, 4, and 5. The handles 55 are of the ordinary form, and the side bars and the said cross-bars are preferably constructed of wood, as shown; but the truck-frame may be of any desired construction, as will be readily understood. Suitable leg-standards 6, 60 which are shaped to form hand-grips, project from the under faces of the side bars and are braced by inclined rods or straps 7, extending from the outer ends of the leg-standards and the adjacent side bars. The leg-standards or 65 handles 6 are also connected by braces 8, extending transversely of the truck-frame from the outer ends of the leg-standards or handles 6 to the center of the rear cross-bar 3. Suitable rollers or wheels 9 are mounted upon the 70 under faces of the side bars and located as near as possible to the forward extremities of the same.

Each side bar is notched or recessed, as shown at 10, and across each notch is secured a metallic plate or strap 11 to form a longitudinal slot. The forward ends of the straps or plates are connected by a flat cross-bar 12, which connects the forward ends of the side bars. The bar 12 is constructed of metal, and the side bars are also connected at the inner ends of the notches or recesses 10 by a metal cross-bar 13, and the said side bars 1 are provided in the notches or recesses with metal plates or bars 14, forming linings for the 85 same and adapted to prevent the wood from becoming worn by clamping members 15, which oscillate in the said slots.

The clamping members, which are adapted to engage a box or other load are approximately L-shaped, and their outer portions 16 form jaws for engaging the load, and are provided with flanges or lugs 17, adapted to embed themselves in a wooden box or other receptacle, whereby the load is effectually prevented from slipping. The lugs or flanges 17 are beveled to provide sharp engaging edges, and they are set at an angle when the clamping members are closed and when the truck is in an upright or substantially up- 100

right position, whereby the weight of the load will operate to hold the clamping members in engagement. The inner portions of the clamping members extend through the slots of the 5 sides of the truck-frame and are provided at their inner ends with plates arranged in pairs and extending inward at right angles and forming perforated longitudinal arms 18 for the reception of pivots 19, which pass through 10 perforations of the inner metal cross-bar 13. The perforated arms which extend from the clamping members may be formed in any other desired manner, and the cross-bar 13 is provided at opposite sides with perforations 15 20, arranged at intervals and adapted to receive the pivot 19 to permit the same to be adjusted, whereby the clamping members are adapted to be positioned properly for engaging a load.

20 The pivoted clamping members, which are swung from the cross-bar 13, are adjustably secured to the outer portions of a pair of links or bars 21 and 22, which are connected at their inner portions by a bolt 23 or other 25 suitable fastening device. The outer ends of the bars or members 21 and 22 are provided at intervals with perforations 24 for the reception of the bolt 25 or other suitable fastening device for connecting the outer ends of 30 the bars to the clamping members. The bolt or pivot 23 passes through the inner end of the bar 21, and the other bar 22 is extended beyond the pivot 23 to form an arm 26. The arm 26 is bent laterally to form a foot-piece 35 27, which is adapted to be engaged by the foot of a person, whereby the clamping members are opened preparatory to engaging a load. The foot-piece 27 is also arranged to engage the inner side edge of the bar 21 to limit the 40 outward movement of the bars 21 and 22. When the clamping members are in their engaging position, as illustrated in Fig. 2 of the accompanying drawings, the bars 21 and 22 are arranged at an angle to each other, and 45 when the foot-piece 27 is depressed the bars are swung downward or outward to a position approximately in alinement, the pivot 23 being carried slightly outward beyond the center, whereby the bars or members 21 and 22 50 form a lock for holding the pivoted clamping members in their open position.

The bars or members 21 and 22 are also connected by a short link 28 with the inner portion of a foot-lever 29, which is fulcrumed 55 between its ends on an oscillatory link 30. The foot-lever, which is preferably constructed of a single piece of metal, is bent to form an outer loop and two sides, as shown. The sides of the foot-lever are spaced apart to receive the connecting-link 28 and the fulcrumed link 30. The fulcruming-link 30 consists of a single piece of metal which is doubled to 60 form a straight portion or shank and which is spread at one end of the spaced portion or 65 shank to form arms. The arms are pivoted

by a bolt 31 or other suitable fastening device to an approximately U-shaped bracket-piece 32, which is secured to the under face of the outer metallic cross-bar 12. The link 30 is connected to the foot-lever at a point between the ends thereof by a bolt 33, and it is adapted to oscillate to permit a limited end-wise movement of the foot-lever. The foot-lever moves inward and outward as the bars or members 21 oscillate. The connecting-link 28 is preferably twisted between its ends to arrange its terminals at right angles to each other, as shown.

The truck is designed especially for carrying a series or tier of boxes of oranges or 80 lemons; but it is adapted for handling various other kinds of merchandise, as will be readily understood. It is placed in an upright position against the load, with its pivoted clamping members open or spread. The foot-lever 85 is then depressed to cause the clamping members to engage the load, and the truck is then tilted backward to raise the load from the ground or other supporting-surface. The weight of the load resting upon the jaws of 90 the pivoted clamping members holds the latter firmly in engagement with the load and effectually prevents the clamping members from accidentally opening and releasing the load. When it is desired to deposit the load, 95 the truck is brought to a perpendicular position to permit the load to rest upon the supporting-surface, and the clamping members, which are thereby relieved of strain, may be readily swung out of engagement with the 100 load by depressing the foot-piece 27.

What I claim is—

1. The combination with a truck, of clamping members movable transversely of the truck to clamp and release the load, and operating mechanism positively actuated by the foot to move the clamping members in each direction, and arranged to lock the clamping members in their open position and to permit them to swing freely therefrom when released, substantially as described.

2. The combination with a truck, of clamping members movable inward and outward to clamp and release the load, and means for enabling the clamping members to be positively moved in each direction by the foot, and arranged to lock the clamping members in their open position, substantially as described.

3. The combination with a truck, of clamping members movable inward and outward to clamp and release the load and having load-engaging portions lying beyond the truck, and means for enabling the clamping members to be positively moved in each direction by the foot, and arranged to lock the clamping members in their open position, substantially as described.

4. The combination with a truck, of angular clamping members pivotally connected with the truck and movable inward and outward to

clamp and release the load, and means for enabling the clamping members to be positively moved in each direction by the foot, and arranged to lock the clamping members in their open position, substantially as described.

5. The combination with a truck, of angular clamping members pivotally connected with the truck and movable inward and outward to clamp and release the load and provided with load-engaging portions lying beyond the truck, and means for enabling the clamping members to be positively moved in each direction by the foot, said means forming a lock for holding the clamping members in their open position, substantially as described.

6. The combination with a truck, of clamping members movable inward and outward to clamp and release the load, and operating mechanism adapted to lock the clamping members in their open position and embodying a foot-piece in operative relation with the clamping members for enabling the same to be positively moved in one direction by the foot, and a foot-lever for enabling the clamping members to be positively moved in the opposite direction by the foot, substantially as described.

7. The combination with a truck, of clamping members movable inward and outward to clamp and release the load and provided with load-engaging portions lying beyond the truck, and operating mechanism forming a lock for holding the clamping members in their open position and embodying a foot-piece in operative relation with the clamping members for enabling the same to be positively moved in one direction by the foot, and a foot-lever for enabling the clamping members to be positively moved in the opposite direction by the foot, substantially as described.

8. The combination with a truck, of angular clamping members pivotally connected with the truck and movable inward and outward to clamp and release the load and provided with load-engaging portions lying beyond the truck, and operating mechanism forming a lock for holding the clamping members in their open position and embodying a foot-piece in operative relation with the clamping members for enabling the same to be positively moved in one direction by the foot, and a foot-lever for enabling the clamping members to be positively moved in the opposite direction by the foot, substantially as described.

9. The combination with a truck, of pivoted clamping members movable inward and outward to engage and release the load and having load-engaging portions lying beyond the truck, bars disposed transversely of the truck and connected with each other and with the clamping members, and arranged to lock the clamping members in their open position, and operating mechanism connected with the bars to open and close the clamping members, substantially as described.

10. The combination with a truck, of clamp-

ing members movable transversely of the truck to clamp and release the load, transversely-disposed bars connected with each other and with the clamping members, and arranged to lock the latter in their open position, and means for operating the bars to open and close the clamping members, substantially as described.

11. The combination with a truck, of clamping members movable inward and outward to clamp and release the load, bars disposed substantially transversely of the truck and connected with the clamping members and with each other, and arranged to lock said clamping members in their open position, and means for enabling the bars to be positively actuated in each direction by the foot to effect the opening and closing of the clamping members, substantially as described.

12. The combination with a truck, of clamping members movable inward and outward to clamp and release the load, bars connected with the clamping members and with each other and movable in opposite directions to open and close the clamping members, and arranged to lock the latter in their open position, and means for enabling the bars to be positively moved in both directions by the foot, substantially as described.

13. The combination with a truck, of clamping members movable inward and outward to clamp and release the load, bars disposed transversely of the truck and connected with each other and with the clamping members and movable in opposite directions to open and close the latter, said bars being arranged to lock the clamping members in their open position, a foot-piece for enabling the bars to be positively moved in one direction by the foot, and a foot-lever for enabling the bars to be positively moved in the opposite direction by the foot, substantially as described.

14. The combination with a truck, of clamping members movable inward and outward to clamp and release the load, bars connected with each other and with the clamping members and movable in opposite directions to open and close the clamping members, and arranged to lock the latter in their open position, and operating mechanism for enabling the bars to be positively actuated by the foot in both the opening and closing movements of the clamping members, substantially as described.

15. The combination with a truck, of clamping members movable inward and outward to clamp and release the load, bars pivotally connected with the clamping members and with each other and movable in opposite directions to carry the pivots thereof into and out of substantial alinement for opening and closing the clamping members and for locking the same in an open position, and means for operating the bars, substantially as described.

16. The combination with a truck, of clamp-

- ing members movable inward and outward to clamp and release the load, bars connected with the clamping members and movable in opposite directions to open and close the same 5 and for locking the clamping members in an open position, and means for operating the bars and for carrying the same into and out of their locked relation, substantially as described.
17. The combination with a truck, of clamp- 10 ing members movable inward and outward to clamp and release the load, bars connecting with the clamping members and arranged at an angle to each other when the clamping members are in engagement with the load, said 15 bars being adapted to lock the clamping members in their open position, and means for operating the bars for swinging the same from such position to a position with their pivots in substantial alinement to lock the clamping-bars in 20 an open position, substantially as described.
18. The combination with a truck, of clamp- 25 ing members movable inward and outward to clamp and release the load and provided with load-engaging portions lying beyond the truck, bars connected with the clamping members and movable in opposite directions to open and close the same and for locking the clamping members in an open position, and means for operating the bars to carry the same 30 into and out of their locked relation, substantially as described.
19. The combination with a truck, of angular clamping members pivotally connected with the truck and arranged to swing inward 35 and outward to clamp and release the load and provided with load-engaging portions lying beyond the truck, bars connected with the clamping members and with each other and movable in opposite directions to open and 40 close the clamping members and for locking the same in an open position, and means for operating the bars for carrying the same into and out of a locked relation, substantially as described.
- 45 20. The combination with a truck, of pivoted clamping members, bars pivotally connected with each other and with the clamping members, one of the bars being extended inward beyond the other and provided with a 50 foot-piece adapted to be engaged by the foot to move the bars in one direction, and means for moving the bars in the opposite direction, substantially as described.
21. The combination with a truck, of clamp- 55 ing members movable inward and outward to engage and release the load, bars connected with the clamping members and with each other, the inner end of one bar being extended beyond the other and provided with a foot- 60 piece arranged to be engaged by the foot to move the bars in one direction, and a foot-lever for moving the bars in the opposite direction, substantially as described.
22. The combination with a truck, of clamp- 65 ing members movable inward and outward to engage and release the load, and bars connected with the clamping members and with each other, the inner end of one of the bars being extended beyond the other and provided with a foot-piece arranged to be engaged by the 70 foot, substantially as described.
23. The combination with a truck, of pivoted clamping members, transverse bars pivoted at their outer ends to the members and similarly connected at their inner ends and arranged to swing in opposite directions to carry the pivots into and out of substantial alinement, to lock the clamping members in their open position and to release them therefrom, a movably-mounted fulcrum, and an operating-lever mounted on the fulcrum and connected with the bars, substantially as described. 75
24. The combination with a truck, of clamp- 80 ing members movable inward and outward to engage and release the load, approximately 85 transverse bars connected with the clamping members and arranged to swing in opposite directions to open and close the same, said bars being adapted to lock the clamping members in their open position, a fulcrum-link 90 pivoted at its outer end to the truck and arranged at an angle to the frame thereof, and a foot-lever fulcrumed between its ends on the link and connected at its inner end with the bars, substantially as described. 95
25. The combination with a truck, of clamp- 100 ing members movable inward and outward to clamp and release the load, approximately transverse bars pivotally connected with the clamping members and with each other and arranged to swing in opposite directions to carry the pivots thereof into and out of substantial alinement, one of the bars being provided with an extension arranged to engage the other bar, and a foot-lever connected with the bars, substantially as described. 105
26. The combination with a truck, of clamp- 110 ing members composed of outer engaging portions or jaws, transverse arms extending inward from the same, and longitudinal arms arranged at the inner ends of the transverse arms and pivotally connected with the truck, approximately transverse bars connected with the clamping members and with each other and movable in opposite directions to open and 115 close the members, and arranged to lock the latter in their open position, and means for operating the bars, substantially as described. 120
- In testimony that I claim the foregoing as my own I have hereto affixed my signature in the presence of two witnesses.
